UNITED STATES PATENT OFFICE.

ARTHUR GRAY, OF NAPLES, MAINE.

WASHING-MACHINE.

Specification of Letters Patent No. 24,116, dated May 24, 1859.

To all whom it may concern:

Be it known that I, ARTHUR GRAY, of Naples, in the county of Cumberland and State of Maine, have invented an Improved 5 Washing-Machine; and I do hereby declare that the same is fully described and represented in the following specification and the accompanying drawings, of which—

Figure 1, is a top view; Fig. 2, a front 10 elevation; Fig. 3, a longitudinal section, and Fig. 4, a transverse section.

In the said drawings, A, represents an elongated tub or reservoir, provided with a series of fluted rollers, B, B, B, such series 15 being arranged at or near to its middle part and just above its bottom as shown in Figs. 3 and 4. In connection with the said series of rollers, a fluted presser or bucking board, C, is employed, it being affixed to a bent 20 lever, D, which is connected with one side of the reservoir, A, by means of a universal joint, E, or so that the said bucking board, C, may not only be moved in vertical direction with the lever as the latter is turned 25 upward or downward, but also be moved in horizontal direction with the said lever. Such universal joint, E, is composed of a swivel or piece of metal, a, having the lever hinged or jointed to it and so as to be capable of being turned vertically on a fulcrum, b, the piece of metal being applied to a vertical spindle, c, in such manner as to enable it to be turned horizontally thereon. The 30 said spindle plays freely in a vertical direction within a bearing, d, and a thimble or socket piece, e. In this latter, there is a helical spring, f, against which the spindle rests, such spindle being provided with a shoulder, g, for the universal joint piece, E, 35 to bear against. The under surface or side of the bucking board, C, is fluted horizontally. 40

In using the machine so constructed, an

attendant grasps the handle, i, of the lever, D, in one hand and raises the lever and the bucking board with it so as to enable the clothes to be washed, to be laid upon the series of fluted rollers, the tub being supposed to be provided with water or suds or other suitable washing liquid. After having 45 deposited the clothes upon the rollers, he should force the bucking board downward upon them and vibrate it to and fro over the rollers. Occasionally, while doing this or at other times, when desirable—he may use the 50 bucking board, in the manner of a beater by moving it upward and downward smartly upon the clothes, all of which will contribute 55 to cleanse them to excellent advantage.

By the employment of a spring in connection with the universal joint (as above set forth) the bucking board is rendered capable of accommodating itself to the mass of clothing, and besides such spring greatly relieves the hand and arm of the operator 60 from the effects of percussion or downward blows while the bucking board is being moved up and down and with respect to the clothes.

A washing machine of the above kind is 70 not only simple in construction and unique in its operation but is of much utility and can be constructed at a very little cost.

I claim—

The improved washing machine as made 75 with a set of fluted rollers and a fluted presser or bucking board, arranged, constructed and applied to the reservoir substantially as described, in order to enable the clothes to be both rolled and beaten as 80 specified, during the operation of washing the same.

ARTHUR GRAY.
